UNITED STATES PATENT OFFICE.

HARRY F. ROACH, OF ST. LOUIS, MISSOURI.

RAIL-JOINT.

1,231,791.

Specification of Letters Patent.

Patented July 3, 1917.

Application filed May 3, 1915. Serial No. 25,461.

To all whom it may concern:

Be it known that I, HARRY F. ROACH, a citizen of the United States, residing at St. Louis, Missouri, have invented a certain new and useful Improvement in Rail-Joints, of which the following is a full, clear, and exact description, such as will enable others skilled in the art to which it appertains to make and use the same.

This invention relates to rail joints, and has for its main object to provide an inexpensive, light-weight rail joint which is so designed that the wave motion of the rails throughout the track is continued uniformly through the joints on which the rails rest, thereby eliminating hard spots in the track and permitting practically equal deflection throughout the track.

Another object is to provide a rail joint that can be made as strong and stiff as desired without liability of causing the joint to break the rails or the rails to break the joint, and which is so designed that the tie reactions throughout the entire track, including the joint tie reactions, are practically the same.

And still another object is to provide a rail joint that is more efficient in every respect than the angle bar splice member now used extensively for connecting rails together and which can be manufactured and sold at a cost that is as low or lower than the angle bar splice member now in common use. Other objects and desirable features of my invention will be hereinafter pointed out.

The rail joint herein described embodies all of the good features and characteristics of the so-called Roach rail joint that is now in extensive use, but it is so designed that it contains less metal and can be supported by a single track tie. It can either be rolled, forged or formed from cast metal, and it is provided with an integral rail-supporting portion which is so designed that the rails which rest on the same have the effect of being hinged to the joint at the center of the joint. Said rail-supporting portion serves as the base plate of the joint and the underside of the same is flat or provided with a horizontally-disposed bearing surface at the center of the joint so as to enable the joint to be mounted on a tie arranged directly underneath the terminals of the rails. In one form of my invention said base portion is comparatively short or of approxi-

mately the same length as the width of a track tie, and in another form said base portion extends the entire length of the joint. In both forms, however, the underside of the base portion is flat or provided with a horizontally-disposed bearing surface which is located at the center of the joint.

Figure 1 of the drawings is a side elevational view, partly broken away, of a rolled rail joint constructed in accordance with my invention.

Fig. 2 is an end elevational view of said joint, showing one of the side members of the joint in vertical section.

Fig. 3 is a side elevational view, partly broken away, of a rail joint of the general type illustrated in Figs. 1 and 2, but formed from cast metal.

Fig. 4 is an end elevational view, partly in vertical section, of the rail joint shown in Fig. 3.

Fig. 5 is a side elevational view of a cast metal rail joint constructed in accordance with my invention, but provided with a one-piece base plate for supporting the rails.

Fig. 6 is a vertical cross-sectional view of the joint shown in Fig. 5; and

Fig. 7 is a side elevational view, showing the inner side of the rail joint member illustrated in Fig. 5.

Referring to Figs. 1 and 2 of the drawings which illustrate a rolled rail joint constructed in accordance with my present invention, A designates two members that are arranged on opposite sides of the rails, as shown in Fig. 1, each of which is provided with a vertically-disposed web 1 that extends longitudinally of the rails, and a horizontally-disposed base plate 2 that extends the entire length of the joint. Each of the base plates 2 is provided on its top face and at approximately its center with a flat surface 3, as shown in Fig. 1, on which the end portions of the base flanges of the rails rest, the remaining portions of the top face of said base plate being inclined downwardly from the rail-supporting surface 3 so as to prevent the base flanges of the rails from normally resting on the end portions of the base plates 2. Each of the members A is provided on its inner side with a portion 4 that bears upon the top faces of the base flanges of the rails and thus securely clamps the rails down upon the flat rail-supporting surface 3 at the center of the joint. The underside of each of the base

plates 2 is flat or parallel throughout its entire length with the rail-supporting surface 3 on the top face of the base plate, so as to cause the members A to bear squarely 5 and evenly upon a track tie B that is arranged either at the center of the joint in vertical alinement with the terminals of the rails, as shown in Fig. 1, or at a point near one end of the joint. A joint of the construction above described can be made much shorter than the so-called Roach rail joint now in general use, owing to the fact that the joint is so designed that it can be supported by a single tie arranged either at the 10 center of the joint or at one end of the same, this being possible on account of the fact that the underside of the base portion of the joint is parallel throughout its entire length with the rail-supporting surface 3 on 15 which the ends of the rails rest. 20

The advantage of a rail joint of this construction is that only the ends of the rails normally rest on the joint, thereby causing the rails to be practically hinged to the joint 25 at the center of the joint. When the joint is in use the wave motion of the rails throughout the entire track is continued uniformly through the joints, and consequently, the deflection throughout the entire track is 30 practically equal, there being no hard spots in the track and no liability of reverse strains being created in the joint. The joint can be made as strong and stiff as desired without liability of causing the joint to break 35 the rails or the rails to break the joint, as no portions of the joint bear against the undersides of the heads of the rails and the joint is so designed as to permit the rails to deflect within the joint at the ends of the 40 joint, the joint merely serving to hold the abutting rails in longitudinal alinement with each other and to hinge the two rails together in such a way that the rails can deflect under load without liability of rocking 45 the tie that supports the joint. In a rail-way track equipped with joints of the construction above described the joint ties or the ties that support the joints require no more lifting or raising than the intermediate ties on which the rails rest, the tie reactions throughout the entire track, including the joint ties, being practically the same. 50

In the form of my invention illustrated in Figs. 3 and 4, the members A' that are arranged on opposite sides of the rails are formed from cast metal and are of substantially the same design as the rolled members A shown in Figs. 1 and 2, except that the base portions 2^a of the members A' are 55 shorter than the joint and of approximately the same length as the width of the tie B on which the joint rests. Another slight change consists in reducing the length of the portions 4^a of the members A' that hold 60 the base flanges of the rails firmly down 65

upon the rail-supporting surfaces 3 on the base plates 2^a, said portions 4^a being located only at the center of the joint, as shown in Fig. 3, instead of extending throughout the entire length of the joint, as in the construction shown in Fig. 1. The vertical webs 1 of the members A' are also preferably provided on their inner sides with integral, inclined braces 5 that reinforce and strengthen the horizontally-disposed ribs or flanges 6 at 70 the upper edges of the members A'. On the outer sides of said webs are oppositely-inclined braces 5^a that extend from the base plates to the horizontally-disposed flanges 6 at the upper edges of said webs. 75

The joint illustrated in Figs. 5 to 7, inclusive, is formed from cast metal and consists of a member C arranged at one side of the rails and provided with a comparatively wide base plate 2^b that extends underneath 80 the base flanges of the rails, as shown in Fig. 6, the chief distinction between this form of rail joint and the ones illustrated in Figs. 1 to 4 being that it is provided with a one-piece base plate, instead of a longitudinally-divided base plate. A member 7 is arranged directly opposite the vertical web of the member C on the opposite side of the rails so as to coöperate with the member C to hold the rails in longitudinal alinement with each 85 other. On the top face of the base plate 2^b of the member C is a flat, horizontally-disposed surface 3 on which the terminals of the rails rest. The remaining portions of the top face of said base plate are inclined 90 downwardly in opposite directions from said supporting surface 3, as shown clearly in Fig. 5, so as to prevent the base flanges of the rails from normally resting on any portions of the joint, except the flat surface 3 at the center thereof. Said member C is, of 95 course, provided with a bearing portion 4^b that coöperates with the base flanges of the rails to securely hold them on the flat rail-supporting surface at the center of the joint. 100 The rail joint shown in Figs. 5 to 7 is also provided with a novel means for preventing the rails from kinking when the end bolts of the joint are tightened, said means consisting of integral, inwardly-projecting lugs 8 on the inner side of the web of the member C arranged at the opposite ends of the same, 105 as shown in Fig. 7. When the end bolts of the joint are tightened said lugs 8 bear against the vertical webs of the rails, as 110 shown in Fig. 6, and thus prevent the rails from being drawn toward the member C to such an extent that the rails will become kinked or bent. This feature is common to the Roach rail joint, but none of the rail joints illustrated in my various prior patents are provided with integral lugs arranged on the inner side of the joint member at the 115 ends thereof for accomplishing this result. 120

In the form of my invention illustrated 125

in Figs. 5 to 7 the base plate is provided with a hole 9 for receiving spikes 10 that engage the base flanges of the rails on the gage side of the track, and thus securely hold the rails in position in case the bolt nuts on the bolts (not shown) that pass through the rails and the joint become displaced or stripped off by a derailed wheel or from any other cause, these spike holes 9 being so positioned with relation to the flat rail-bearing surface 3 on the base plate that there is no tendency for the spikes in the same to work out of the ties. On the opposite side of the base plate 2^b, a notch 11 is formed in the edge of the same, as shown in Fig. 5, for receiving a spike 12 that is located at the center of the joint approximately intermediate the two spikes 10 on the opposite side of the joint.

Having thus described my invention, what I claim, and desire to secure by Letters Patent, is:

1. A rail joint provided with a rigid base plate having a flat rail-bearing surface on its top face that supports the ends of the rails and normally holds the base flanges thereof out of engagement with the end portions of the base plate, thereby permitting the rails to deflect downwardly slightly at the ends of the joint when a load passes over the joint, said base plate being provided on its underside with a flat tie-engaging surface that is located at the center of the joint, thereby enabling a track tie to be arranged directly underneath the terminals of the rails.

2. A rail joint, comprising a rigid base plate provided with a top face which is so formed that only the extreme end portions of the base flanges of the rails will normally rest on same, the underside of said base plate being flat throughout its entire length and the joint being so designed that the rails can deflect downwardly slightly at the ends of the joint when a load passes over the joint.

3. A rail joint having a rail-supporting portion which is so designed that only a comparatively small area of the top face thereof will normally be engaged by the base flanges of the abutting rails that rest on same, thereby permitting the rails to deflect slightly under load at the ends of the joint so as to cause the wave motion of the rails to be continued uniformly through the rail joints throughout the entire track, the underside of said rail-supporting portion being so formed that it will rest firmly and squarely upon a tie that is located at the center of the joint.

4. A rail joint having a rigid rail-supporting portion provided on its top face with a flat rail-bearing surface which is arranged between two oppositely-inclined surfaces that are normally spaced away from the base flanges of the rails so as to permit

the rails to deflect downwardly slightly at the ends of the joint when a load passes over the joint, the underside of said rail-supporting portion being flat and parallel throughout its entire length to the flat surface on the top face of same on which the terminals of the rails rest.

5. A rail joint having a base plate of less length than the portion of the joint that extends alongside of the rails, said base plate being provided on its top face with a flat rail-bearing surface located intermediate two oppositely-inclined surfaces that are normally spaced away from the base flanges of the rails and which permit the rails to deflect downwardly slightly at the ends of the joint when under load, the underside of said base plate being flat or disposed horizontally to the flat rail-bearing surface on the top side of same.

6. A rail joint, comprising a member that extends alongside of the rails and provided with a base portion whose top face is so formed that only the ends of the abutting rails will normally engage same, the underside of said base portion being flat throughout its entire length and parallel to the surface on said top face on which the abutting ends of the rails rest, means on said member which bears against the top faces of the base flanges of the rails so as to prevent them from rising upwardly off the supporting surface on said base portion, integral lugs on said member arranged adjacent the ends of same which are adapted to bear against the vertical webs of the rails so as to prevent the rails from kinking when the end bolts of the joint are tightened.

7. A rail joint, comprising a cast member that extends along one side of the rails and which comprises a base portion and a vertically-disposed web integrally connected together, said base portion having an integral horizontally-disposed flat surface on the top face thereof arranged intermediate oppositely-inclined surfaces that are normally spaced away from the base flanges of the rails, a bearing on the inner side of said web that acts upon the base flanges of the rails and holds them on said flat surface, a flange extending longitudinally along the upper edge of said web, and integral, inclined braces on the inner side of said web arranged intermediate said flange and said bearing.

8. A rail joint designed to be supported by a single tie and provided with a base plate having an integral rail-bearing surface on which the terminals of the rails rest, the top face of said base plate being so constructed that the joint permits the rails to deflect downwardly slightly at the ends of the joint when under load, thereby permitting wave motion to exist without rocking or rolling the joint tie.

9. A rail joint designed to be supported by a single tie and having a base plate provided on its top face with an integral rail-bearing surface that is shorter than the base plate and provided on its bottom face at a point in vertical alinement with said rail-bearing surface with a tie-engaging surface that is parallel to said rail-bearing surface.
10. A one-tie rail joint provided with a base plate that extends under the rails, and a horizontally-disposed web that extends longitudinally of the rails, said base plate having an integral rail-bearing surface of less dimensions than the base plate on which the terminals of the rails rest, and inclined braces on the outer side of said web integrally connected to said base plate.
11. A one-tie rail joint provided with a base plate that has an integral rail-bearing surface at approximately its center which is of less area than the portion of the base plate that rests on the joint tie, said base plate having openings for receiving rail spikes or similar devices that engage one side of the base flanges of the rails in proximity to the point where the rails rest on said bearing surface.
12. A one-tie rail joint provided with a base plate that has an integral rail-bearing surface at approximately its center which is of less area than the portion of the base plate that rests on the joint tie, said base plate having openings for receiving rail spikes or similar devices that engage one side of the base flanges of the rails in proximity to the point where the rails rest on said bearing surface, and a spike opening in the opposite side of said base plate arranged approximately intermediate the openings first referred to.
13. A one-tie rail joint provided with a

base plate that has an integral rail-bearing surface at approximately its center which is of less area than the portion of the base plate that rests on the joint tie, said base plate having openings for receiving rail spikes or similar devices that engage one side of the base flanges of the rails in proximity to the point where the rails rest on said bearing surface, a spike opening in the opposite side of said base plate arranged approximately intermediate the openings first referred to, a vertically-disposed web that extends longitudinally of the rails, and oppositely-inclined braces on the outer side of said web integrally connected at their lower ends to said base plate.

14. In a rail joint of the type in which the rails can deflect downwardly slightly at the ends of the joint under load, the combination of a base plate that is shorter than the portion of the joint which coöperates with the webs of the rails, a bearing on said base plate shorter than said plate for supporting the ends of the rails, and means that prevents the rails from kinking when the end bolts of the joint are tightened.

15. In a rail joint of the type in which the rails can deflect downwardly slightly at the ends of the joint under load, the combination of a base plate shorter than the joint, and means for preventing the rails from kinking when the end bolts of the joint are tightened.

In testimony whereof I hereunto affix my signature in the presence of two witnesses, this first day of May, 1915.

HARRY F. ROACH.
